UNITED STATES PATENT OFFICE.

LAWRENCE M. ENDRES, OF CROSS PLAINS, WISCONSIN.

SAW-FEEDER.

933,965.

Specification of Letters Patent. Patented Sept. 14, 1909.

Application filed January 30, 1909. Serial No. 475,117.

To all whom it may concern:

Be it known that I, LAWRENCE M. ENDRES, a citizen of the United States, and resident of Cross Plains, in the county of Dane and State of Wisconsin, have invented certain new and useful Improvements in Saw-Feeders; and I do hereby declare that the following is a full, clear, and exact description thereof.

10 The object of my invention is to provide a simple, effective, and economical oscillating feed-rack for cross-cut saws, the construction and arrangement being such that a log may be placed upon the rack, manually gripped and fed to the saw, the said rack being also capable of detachment for convenience when the saw is in transportation.

15 The invention therefore consists in certain peculiarities of construction and combination of parts as fully set forth hereinafter with reference to the accompanying drawings and subsequently claimed.

20 In the drawings: Figure 1 represents a side elevation of a portion of a saw and its frame having attached thereto a feed-rack embodying the features of my invention, parts being broken away to better illustrate structural features; Fig. 2, a plan view of the same showing the feed-rack partly swung over toward the saw and in section, as indicated by line 2—2 of Fig. 1; Fig. 3, a front view of the saw and feed-rack, the latter being partly in section, as indicated by line 3—3 of Fig. 1; Fig. 4, a detail longitudinal 25 sectional view of the feed-rack looking toward the rear, the section being indicated by line 4—4 of Fig. 1, and Fig. 5, a detail sectional front view of the device, as indicated by line 5—5 of Fig. 2.

30 Referring by character to the drawings, A, A', indicate the front and rear sills respectively of a saw-frame provided with boxes constituting bearings for a saw-arbor B, which arbor carries a circular saw C and is driven by a suitable pulley, (not shown) carried by the arbor. Secured to the front sill A, upon the feed-side of the saw, is a 35 forwardly extending knee 1 having a fin-back 2, which serves as a primary log support, the knee being also provided with a stop-lug at its end. A trunnion 3 is suspended under the knee from the saw-sill A, by means of a bail 4, that is linked over a hook 5, which hook is secured to the under- 40 side of the sill, the ends of the bail being provided with eyes for the reception of the

trunnion. The trunnion is held trussed in relation to the saw-frame by means of tie-rod 6 pivotally mounted upon the front sill A rearward of the saw, there being a supplementary tie-rod 7 in pivotal connection with the rear sill A', which pivotal connection is axially aligned with the pivotal mounting of the tie-rods 6. All of the tie-rods are provided with eyes through which the trunnion passes, the said trunnion being threaded at its ends for the reception of tie-rod retaining nuts, as shown. The eyes of the bail 4 and tie-rods 6 are spaced apart upon the trunnion 3 to provide bearing space 45 for front and rear legs 8, 8^a, of an oscillating feed-rack, which legs have recessed ends adapted to fit upon the bearing spaces of the trunnions.

50 The upper ends of the feed-rack legs 75 straddle the knee 1 and are connected above the same by a head-block 9, the latter being arranged to abut the stop-lug of said knee when said feed-rack is in its extreme forward position, as shown in Fig. 1 of the 55 drawings. Extending rearwardly from the legs 8, 8^a, are parallel arms 10, 10^a, which are disposed approximately upon the same horizontal plane as the fin-back 2 of the knee. The upper faces of the arms are bound with 60 metallic strips, which also extend over the adjacent surface of the head-block 9. One strip is flared upwardly and rearward of the arm to which it is attached and merged into a U-shaped vertically disposed loop 11, 90 which loop is arranged to straddle the saw and forms a log-rest at the back of the feed-rack. The returned bend of the loop is flattened to constitute a rail 11^a that is supported by a foot secured to the rear arm 10^a 65 and runs parallel with and upon the same plane as the before mentioned strips, the front end of the rail being secured to the head-block. This rail 11^a thus forms an intermediate horizontal log-support in connection with the arms and is so disposed with 70 relation to the front arm 10 as to straddle the knee.

75 The rear ends of the arms 10, 10^a are braced by metallic struts 12, which in turn 105 are bolted to the lower extremities of the legs, the bolts also serving as retainers for a cross-strip 13 that connects and stiffens the legs at this point. The front arm 10, as shown, projects forward at the feed-rack legs, and is 110 provided with a hand-grip 14, whereby the feed-rack is manually oscillated to feed the

2
logs rearwardly to the saw and retracted therefrom after each cut. Fulcrumed to the front leg 8 of the feed-rack is a log-gripping lever 15, which lever is preferably serrated for that portion of its length extending above the arm 10, 10^a, and terminates with a spade-handle 16 above the serrated portion thereof. This lever is provided for the purpose of gripping or chucking a log 10 between its serrated face and the U-shaped loop 11, the said lever being guided between the adjacent arm 10^a and an offset rail 17 that is secured to said arm. The rail 17 also serves, in conjunction with the adjacent arm, 15 as a support for the body of the log during the operation of severing the end thereof, the rail being vertically upturned at its rear end to facilitate its function.

From the foregoing description, taken in 20 connection with the drawings, it will be seen that the legs 8, 8^a are so spaced apart, that when the feed-rack is moved rearward in its sawing-position, said legs will straddle the sill A and thus be prevented from lateral 25 play, and when said feed-rack is thrown forward lateral play thereof is resisted by the struts 12 taken in connection with the front leg 8.

In the operation, one end of a log is 30 dropped into the saddle formed by the upper portion of the feed-rack from the side of the machine carrying the saw, the opposite end of the log being conveniently supported upon the ground or otherwise. Holding the 35 hand-grip 14 with the left hand, the operator then grasps the lever 15 and forces the log against the U-shaped loop or back-rest, whereby it is chucked between the same and the serrated edge of the lever. By lifting 40 upon the hand-grip 14, while holding the chucked log, the entire feed-rack will swing over and cause the log to be engaged by the saw, the cutting being regulated by the speed with which the operator moves said feed- 45 rack rearward, which movement requires no appreciable force after the log has been moved rearward a sufficient distance that its weight is upon the opposite side of the fulcrum upon which the aforesaid feed-rack oscillates. When the desired length is cut from 50 the log, the feed-rack is retracted and the log moved up for new cut, and so on. Thus it is apparent that logs of great weight may be handled and cut into lengths by a single operation, the feed-rack being so balanced as to have this feature in mind.

When not in use or for facilitating transportation, the feed-rack may be lifted from

its trunnion 3 and conveniently stored upon the machine, while the trunnion itself can be 60 swung up and out of the way by disengaging the bail from its hook and looping the former over the knee. Thus should the machine be mounted upon a truck, as commonly done with this type of saws, these parts will all be 65 elevated so as not to form an obstruction when said machine is in transit.

I claim:

1. A sawing-machine having a frame, an arbor supported upon the frame, and a circular saw carried by the arbor; a knee secured to the frame upon the feed-side of the saw, a bail suspended from said frame, a trunnion carried by the bail, tie-rods in connection with the aforesaid frame and trunnion, a feed-rack having supporting-legs mounted upon the trunnion and adapted to extend above said knee, a controlling-handle in fixed relation to the feed-rack, a head-block connecting the legs, arms extending 80 from said legs, a vertically disposed rear log-rest in connection with the arms, the log-rest being arranged to straddle the saw, a forward stop for the aforesaid feed-rack carried by the aforesaid knee, and a log-gripping 85 lever in connection with the feed-rack.

2. A sawing-machine having a frame, an arbor supported upon the frame, and a circular saw carried by the arbor; a knee secured to the frame upon the feed-side of the 90 saw and in the same approximate vertical plane as the latter, a bail suspended from said frame in alignment with the knee, a trunnion carried by the bail, tie-rods in connection with the aforesaid frame and trunnion, a feed-rack having parallel supporting legs mounted upon the trunnion and adapted to extend above said knee, a controlling handle in fixed relation to the feed-rack, a head-block connecting the legs, arms extending 95 from said legs, a vertically disposed U-shaped rear log-rest in connection with the arms, the U-shaped log-rest being arranged to straddle the saw, a forward stop for the aforesaid feed-rack carried by the aforesaid knee, and a log-gripping 100 lever in connection with the feed-rack.

In testimony that I claim the foregoing I have hereunto set my hand at Cross Plains, in the county of Dane and State of Wisconsin in the presence of two witnesses.
